United States Patent Office.

ISAAC COOK, OF ST. LOUIS, MISSOURI.

Design No. 2,697, dated July 9, 1867.

DESIGN FOR A TRADE-MARK.

The Schedule referred to in these Letters Patent and making part of the same.

TO ALL WHOM IT MAY CONCERN:

Be it known that I, ISAAC COOK, of the city of St. Louis, in the county of St. Louis, and State of Missouri, have originated and designed a new Design for a Trade-Mark, of which the following is a full, clear, and exact description, reference being had to the annexed drawing, making a part of this specification.

My design consists of a grape vine and leaves, cluster of grapes, and tendrils, arranged upon a frame, in combination with the words "American Wine Co." and "St. Louis, Mo.," with the ornaments α α' , disposed substantially in the position shown in the drawing annexed hereto.

This design is intended to be used both in the form of an engraving and in the form of a brand, and when used in the latter the frame, vine, tendrils, and the words "American Wine Co.," "St. Louis, Mo.," and the ornaments α α' , will have such breaks in them as may be necessary to give the requisite strength to the stencil or other plate by which the impression is made.

What I claim as my invention, and desire to secure by Letters Patent, is—

The design for a trade-mark as herein set forth and shown.

ISAAC COOK.
